MECHANISM FOR ADJUSTING AND SETTING
RADIOS OR OTHER APPARATUS

Freeman H. Owens, New York, N. Y.

Application June 14, 1944, Serial No. 540,292

27 Claims. (Cl. 250—20)

1

The herein disclosed invention relates to the adjusting and setting of different kinds of apparatus, particularly radio apparatus.

Special objects of the invention are to provide mechanism of relatively simple construction, which can be produced at low cost and which will operate to perform such related effects as turning a radio set on, selecting a particular wave band, tuning in a station in that particular selected wave band and adjusting to the desired sound volume.

Further special objects are to provide practical mechanism which will accomplish any or all of the actions mentioned in one operation or all as a part of the same operation.

A further object is to provide mechanism such as outlined which may be arbitrarily actuated at any time manually or which may be automatically actuated at certain desired preselected times.

Another object of the invention is to effect automatic locking of the parts in the particular wave band selected, during the period it is desired to receive the station in that particular selected wave band.

Another object is to so construct the mechanism as to take up but small space and so be readily adaptable for direct incorporation in a standard radio receiving set or into a small unit which may be used in conjunction with an ordinary radio receiver.

Additional objects are to provide such mechanism in a form which will operate smoothly, quietly and with a positive action.

Other objects and the novel features of construction, combinations and relations of parts by which all purposes of the invention are attained will appear as the specification proceeds.

The drawings accompanying and forming part of the specification illustrate a present practical embodiment of the invention, but structure may be modified and changed all within the true intent and broad scope of the invention as hereinafter defined and claimed.

Fig. 1 in the drawings is a front elevation of a radio receiver having features of the invention incorporated therein.

Fig. 2 is an enlarged vertical sectional view as on substantially the plane of line 2—2 of Fig. 1, and showing one of the station selecting slides actuated to effect the turning on of a radio receiver and to accomplish wave band selection, tuning of a station in the wave band selected and setting of the volume control for that particular station.

Figs. 3 and 4 are broken horizontal sectional

views on substantially the lines 3—3 and 4—4, respectively, of Fig. 2, showing the slide first in the actuated or retracted position with the wave band selecting means locked in the position to which it has been adjusted, and then the slide in the projected relation, with the wave band selecting means free for any desired adjustment.

Figs. 5, 6, 7 are broken sectional details, substantially on the lines 5—5, 6—6 and 7—7, respectively, of Fig. 2.

Fig. 8 is a broken front elevation of the guide opening in the front panel for the operating slide.

Fig. 9 is a view of the front end of the slide.

Fig. 10 is a wiring diagram.

In Fig. 1, the invention is shown embodied in a radio receiver of the program preselecting type disclosed in copending application for patent Serial No. 515,853, filed December 27, 1943, now Patent No. 2,432,540, granted December 16, 1947, and comprising a band of keys 10, in line with broadcast time designations on a scale 11, and adapted to be rotated to different station selecting or "off" positions indicated at 12.

The particular instrument shown is designed for receiving any six different stations in any three different wave bands. Accordingly, it is provided with six different control units, numbered 1 to 6. Each of these control units is shown as having a volume control knob 13, and in back of that a tuning knob 14, and a wave band selecting lever 15. These may have suitable dials or markings such as those indicated, including the designations A, B and C, which in this case, may be considered as representing the short wave, broadcast and frequency modulation positions of the wave band selecting levers.

Details of the adjusting and setting mechanism are illustrated in Fig. 2, where the volume control knob 13, is shown fixed on the outer end of a shaft 16, rotatable within the tubular shaft 17, which in turn is rotatable within an outside sleeve or tubular shaft 18. The tuning knob 14, is mounted on the outer end of the inner tubular shaft, back of the volume control knob and the wave band selecting lever 15, is shown fixed to the forward end of the outer tubular shaft back of the tuning knob.

All three concentric shafts are mounted on and carried by a slide 19, in this particular instance, by journalling the forward end of the intermediate tubular shaft in the angularly bent outer end portion 20, of the slide and the inner end of the inside shaft 16, in a bearing lug 21, on the inner end portion of the slide. At its inner

end, the slide is shown as branched in three longitudinal, straight and substantially parallel forks 22, 23, 24. The upper and lower of these are shown used for supporting and guiding the inner end of the slide in openings 25, 26, provided in the partition or bridge wall 27. The outer end of the slide is shown riding in a guide slot 28, in the front wall 29, of the chassis or base structure.

A spring 30, surrounding the intermediate branch or fork 23, by engaging the partition wall 27, thrusts and normally holds the slide outward in the position indicated in Fig. 4.

The inward movement of the slide is utilized for effecting the setting or actuation of two or more rockers, such as, in the case of a radio receiver, may possibly be employed for tuning, volume control, wave band selecting, switching and other like purposes.

In the present illustrative embodiment, one rocker 31, is shown as pivoted at 31a, Fig. 3, in position to be engaged and rocked one way or the other by cam 32, pivotally mounted at 33, on the upper arm of the slide. This rocker is indicated as having an arm 34, which through suitable linkage 34a, may be employed for imparting adjustments to a tuner or other instrument, in accordance with the setting of the cam 32. The central pivot portion of this cam as shown in Fig. 2, is adapted to pass through the opening 35, in the rocker, to enable the horns at 36, 37, at opposite ends of the same to engage the face of the rocker and tip it into different angular positions.

Adjustments of the tuner cam 32, are effected in the present disclosure from a worm 38, on the inner end of the inner tubular shaft 17, in engagement with a corresponding worm gear 39, journaled on the slide at 40, and carrying a pinion 41, in mesh with an intermediate or idler pinion 42, engaging the gear segment 43, on the back of such cam.

A rocker such as may be employed for effecting volume control adjustments is illustrated at 44, pivotally mounted for engagement and operation by a second cam 45, centered on the lower end of the slide at 46.

A volume control unit such as might be adjusted from the second rocker 44, is indicated in outline at 47, the rocker being extended at 48, Fig. 7, or the like, for effecting operation of such volume control.

The setting of the second, in this case, volume control cam 45, is shown as effected through a system of irreversible gearing, similar to that for the tuner, consisting of a worm gear 49, fixed on the inner end of inner shaft 16, and engaging a corresponding gear 50, journaled on the slide at 51, and having a pinion 52, in mesh with the gear segment 53, on the back of the cam.

The rocker for effecting the third function, in this case, the wave band selection, is indicated at 54, pivotally mounted at 55, Fig. 6, below the slide, for actuation by a third cam 56, pivoted on the lower, forward portion of the slide at 57, and adjusted to and held in any one of the three wave band selecting positions by a link 58. The latter is shown pivotally connected at its lower end with the cam, at 59, and as having a rack 60, on the upper, side portion of the same, engaged by a pinion or projecting gear teeth 61, on the side of the outer tubular shaft 18. This spur gear connection between the tubular shaft and link, serves to maintain this cam adjusting link in position between the face of the slide and

the adjoining side of the tubular shaft. The end of rocker 54, may directly connect with the wave band selecting switch 79, as indicated at 80, in Figs. 6 and 10.

In similar manner, the assembly of the tuning and volume adjusting members serves to interlock and maintain those parts in proper relation. The outer tubular shaft 18, supported on the inner tubular shaft, is positioned longitudinally between the angled bearing lug 20, at the front and the worm 38, at the back. This worm is fixed on the intermediate tubular shaft 17, and thus acts as a stop to prevent that shaft pulling forward. Inward movement of this shaft is stopped by engagement with a spacer washer 62, between the two worms. The inner worm 49, is fixed on the inner shaft 16, at the forward side of the bearing lug 21. Consequently, this worm and the shaft to which it is fixed, are located and held in position by the act of assembly and serve in turn to hold the other parts in proper relation.

The adjusting means for both the upper and the lower, the so-called tuner and volume control cams, are irreversible, in the sense that they will be held by their adjusting gearing in the positions in which they have been set by the tuning and volume control knobs.

Similarly, irreversibility is provided for the lower, forward, wave band control cam, in the illustration, by means of a spring pressed ball 63, at one side of the outer shaft member 18, engaging in properly positioned detent seats 64, in the opposing face of the front bearing lug 20, of the slide.

The spring detent 63, is shown as housed within a laterally projecting lug or key 65, on one side of the tubular shaft 18, which will enter any one of the three notches 66, in the front plate 29, of the chassis, to lock the selector in either the A, B or C position. This interlock serves to prevent accidental shifting of the wave band selector, for example, when the slide is in its inward position and the knobs are being adjusted for tuning and volume control purposes. When the slide is in the outward position, Fig. 4, the inner end of the lug 65, will clear the front wall of the chassis and hence at such time, the selector lever 15, may be turned one way or the other to set the wave band selecting cam in any one of its three positions. By engagement in one of the notches 66, on the inward movement of the slide, the key lug 65, prevents any shifting of cam 56, as it strikes the rocker 54. Thus the cam is positively held in its adjusted position during the active part of its stroke. This interlocking arrangement thus relieves the spring detent 63, of any heavy load during the actuating movement of the slide, but the spring detent serves to retain the wave band selecting lever in the selected position, when the slide is out and the selecting lever is unlocked from the chassis panel.

In addition to the three functions described, the slide may be utilized for other, more or less related purposes, such for example, as throwing a switch to turn the receiver "on," following a period in which it may have been turned "off."

In the present illustration, the slide is shown as having a cam shoulder 67, on the upper edge of the same arranged to ride under and lift a bar 68, pivotally supported at its ends at 69. This bar is shown as carrying a projecting lever 70, disposed beneath the core 71, of a so-called "off" magnet 72, and which core is pivotally connected at its upper end with a rocker 72a, carrying the

"on" mercury switch 73, Fig. 1. The switch throwing bar may extend across the top of all the slides, so that it will be actuated by any one of them and it is shown as lightly tensioned downward to engage any one of the cams 67, by a spring 74.

The construction of the slide with spaced arms 22, 24, at the inner end of the same, operating upper and lower rockers, such as for tuning and volume control purposes and the cams below and above the slide, operating in this case wave band selector and switch throwing rockers, provides a balanced construction enabling the slide to smoothly perform these several operations and enabling a relative arrangement of these parts by which any desired timing of such operations may be effected. In the illustration, the cam 67, on top of the slide is positioned to actuate rocker 68, to throw the control switch to the "on" position before the tuning, volume control or band selecting switches are actuated or fully adjusted. The combination furthermore allows for a grouping of the rockers, on different centers, about the slide, as may be necessary to suit different and special requirements of construction, operation and design.

The operation of the slide or slides may be manual or automatic or partly both. For manual operation, the slides may be simply pushed in by pressure on the outer button or knob 13.

In the case of an automatic receiver, such as illustrated, the slides may be actuated by solenoids 75, acting on cores 76, attached to the inner ends of the slides.

To set the receiver illustrated to a desired station, it is only necessary to turn the lever 15, of one of the slides to the A, B or C position, corresponding to the wave band in which that station operates and to then push in that slide and hold it so, while turning knob 14, to tune in that particular station and adjusting knob 13, to the desired sound level.

The rotation of knobs 14 and 13, rocks the cams 32 and 45, and these, through their engagement with rockers 31 and 44, impart the necessary adjustments to the tuner and volume control, to bring in the desired station at the desired volume. The worm gear actuating connections to these cams being irreversible, the cams will stay in these adjusted positions for subsequent automatic or manual operations of the slide. These worm gear connections furthermore are ordinarily sufficiently close fitting to insure continuing accurate tuning and volume control adjustments, but it is contemplated that if found desirable, slack compensating takeups may be incorporated in the lines of adjusting connections from the knobs back to the cams.

If, in the illustration, the control switch 73, is in the "on" position when a slide is actuated, then the cam 67, on the upper edge of that slide, will merely lift the rocker 68. If however, the receiver was "off" prior to such slide operation, the rocker 68, will have the effect of raising the core 71, and rocking the control switch into the "on" position. The forward end of the cam 67, serves in the illustration as a stop shoulder 78, engageable with the front wall of the chassis to limit outward movements of the slide, as in Fig. 4.

While generally preferred to have the slide perform all four necessary functions of turning the set "on," selecting the wave band, tuning and adjusting the volume, it is recognized that in some cases and particularly for the more simple and inexpensive receivers, some one or more of these

particular functions and the parts necessary for that particular function or functions may be omitted.

Operation

The wiring diagram, Fig. 10, may be referred to for a general consideration of the operation.

When the slide 19 at one of the six stations pictured in Fig. 1 is thrust inward by hand or pulled in by its actuating magnet 75, the upper rocker 68, will be raised by cam 67, to raise the core 71, of the "off" solenoid 72, and throw the control switch 73, into the "on" position.

In this inward movement of the station selecting slide, the lower, forward cam 56, will engage the rocker 54, to set the wave band selecting switch 79, in the selected wave band position for the station desired, the upper cam 32, will actuate rocker 31, to adjust the tuner 81, to bring in that station and the lower, rear cam 45, will adjust the rocker 44, to set the volume control 47, to the sound level at which it is desired to have that station come in over loud speaker 103.

The control switch 73, is shown connected by wiring 82, with the radio receiver indicated at 83, so that the set will be turned "on" when the wave band selecting switch, tuning and volume control rockers are actuated to adjust those particular instrumentalities.

The volume control 47, may be constructed as disclosed in copending patent application Serial No. 499,295, filed August 19, 1943, now Patent No. 2,411,891, granted Dec. 3, 1946, with a rotary brush indicated at 84, connected in this case at 48, to be directly operated by the volume control rocker 44. The fader 86, is similarly constructed with a rotary brush 87, connected in this case at 88, with the switch actuating rocker 68, so as to fade out and then fade in the signal, automatically with the slide operation. The cut-off switch enables this fader to be thrown out of action during the operation of tuning the set.

In connection with this fader, there is shown a shorting switch 89, operable by a turn button 90, Fig. 1, to enable the fader being shorted out of the circuit when the slide is held in for the purpose of tuning in a station, adjusting volume or the like. These particular features are not shown in detail, constituting subject matter of a separate copending patent application.

A so-called master volume control is indicated at 91, having a movable brush 92, operable by the knob 93, Fig. 1 and all three volume controls, that is, the "critical" volume control 47, the fader 86, and master volume control 91, are shown connected in series and connected by wiring 94, with the audio section of the radio receiver.

In the diagram, the time key 10 for the 6 a. m. broadcast period is indicated as positioned to connect the 6 a. m. bus wire 95, with the bus 96, for the No. 3 magnet 75. The circuit connections are similar to those disclosed in copending patent applications Ser. 465,155 filed Nov. 10, 1942, now Patent No. 2,403,454, granted July 9, 1946, and Ser. 520,693 filed February 1, 1944, now Patent No. 2,415,843 granted February 18, 1947, including the connection 97, from one side of the transformer secondary 98, to the current supply ring 99, of the time clock 100, and by way of the rotating brush 101, and wiring 102, to the time bus 95, then by way of switch key 10, to the bus 96, No. 3 magnet 75, and return connection 103, to switch terminal 104, rotating contactor 105, switch terminal 106, and wire 107, to the other side of the transformer secondary. This will

effect the energization of the No. 3 magnet and the actuation of the slide 19, controlled by that magnet to effect the several operations above described, at the time determined by the selected time key 10. If in the example supposed the key 10 were in the lower, "off" position, that is connecting the 6 a. m. time bus 95 with the bus for the "off" magnet 72, then that magnet would be energized just as was the No. 3 magnet as last described, but the effect of this "off" magnet would simply be to pull down its core 71 and rock switch 73 to the "off" position, as indicated in broken lines in Fig. 1, thus to interrupt the control circuit and turn the receiver off for that period or up to the time of the first selector key which is set in one of the station selecting positions. Thus the set may be automatically turned off and kept silent for any desired length of time, coming on again automatically only when the time is reached for which some time key has been set at a station desired to be brought in at that time.

What is claimed is:

1. Apparatus for effecting tuning and volume control adjustments of a radio receiver, comprising a plurality of movable station selecting members, a rocker in the path of movement of one portion of said members for effecting tuning adjustments, a rocker in the path of movement of another portion of said members for effecting volume control adjustments, strikers adjustably mounted on the respective portions mentioned of said members for effecting variable adjustments of said tuning and volume controlling rockers and separate hand operable elements on said members for independently adjusting the tuner adjusting and the volume control adjusting strikers on said members.

2. Apparatus for effecting tuning and volume control adjustments of a radio receiver, comprising a plurality of movable station selecting members, a rocker in the path of movement of one portion of said members for effecting tuning adjustments, a rocker in the path of movement of another portion of said members for effecting volume control adjustments, strikers adjustably mounted on the respective portions mentioned of said members for effecting variable adjustments of said tuning and volume controlling rockers, independently adjustable knobs concentrically arranged on each of said station selecting members and irreversible actuating connections from said knobs to the tuner adjusting and volume control adjusting strikers respectively.

3. Apparatus for effecting tuning and volume control adjustments of a radio receiver, comprising a plurality of movable station selecting members, a rocker in the path of movement of one portion of said members for effecting tuning adjustments, a rocker in the path of movement of another portion of said members for effecting volume control adjustments, strikers adjustably mounted on the respective portions mentioned of said members for effecting variable adjustments of said tuning and volume controlling rockers, 65 separate hand operable elements on said members for independently adjusting the tuner adjusting and the volume control adjusting strikers on said members, cam shoulders on other portions of said station selecting members, a rocker 70 positioned for actuation by any one of said cam shoulders and an "on" switch arranged to be operated by said last mentioned rocker.

4. Apparatus for effecting wave band selecting, tuning and volume control adjustments of a ra-

dio receiver, comprising a plurality of movable station selecting members, wave band cams, tuner cams and volume control cams adjustably mounted on different portions of said station selecting members, a rocker for effecting tuning adjustments positioned for engagement by said tuner cams, a rocker for effecting volume adjustments positioned for actuation by said volume control cams, a rocker for effecting wave band selecting adjustments positioned for engagement by said wave band selecting cams and means on each of said station selecting members for independently adjusting the wave band selecting, tuning and volume control cams thereon.

5. Apparatus for effecting wave band selecting, tuning and volume control adjustments of a radio receiver, comprising a plurality of movable station selecting members, wave band cams, tuner cams and volume control cams adjustably mounted on different portions of said station selecting members, a rocker for effecting tuning adjustments positioned for engagement by said tuner cams, a rocker for effecting volume adjustments positioned for actuation by said volume control cams, a rocker for effecting wave band selecting adjustments positioned for engagement by said wave band selecting cams, means on each of said station selecting members for independently adjusting the wave band selecting, tuning and volume control cams thereon, cam shoulders on other portions of said station selecting members, a rocker positioned for actuation by any one of said cam shoulders and an "on" switch arranged to be operated by said last mentioned rocker.

6. Apparatus for effecting wave band selecting, tuning and volume control adjustments of a radio receiver, comprising a plurality of movable station selecting members, wave band cams on said members, tuner and volume control cams adjustably mounted on said members, a wave band selecting rocker mounted in position for actuation by any one of said wave band selecting cams, tuner adjusting and volume adjusting rockers positioned for actuation by said tuner and volume control cams and separate controls on each of said station selecting members for independently adjusting the tuner and volume control cams thereon.

7. In apparatus of the nature disclosed, a slide for effecting adjustment of different members, rockers in the line of movement of said slide and adapted for connection with the members to be adjusted, cams adjustably mounted on said slide in position to engage the respective rockers, independently operable means on the end of said slide for independently and individually adjusting said cams and irreversible operating connections from said independently operable means to said cams.

8. In apparatus of the nature disclosed, an actuating slide, a plurality of adjustable cams on said slide, independently operable means on said slide for individually adjusting said cams and rockers positioned for actuation by said independently adjusted cams.

9. In apparatus of the character disclosed for effecting tuning and volume control adjustments of a radio receiver, a tuner and volume control actuating slide, tuning and volume control knobs on the front end of said slide, independently adjustable cams on said slide, a tuner adjusting rocker positioned for adjustment by one of said cams, a volume controlling rocker positioned for

adjustment by another of said cams and adjusting connections from said tuning and volume control knobs to said tuning and volume control cams.

10. In apparatus of the character disclosed for effecting tuning, volume control and wave band selecting adjustments of a radio receiver, a tuner and volume control actuating slide, tuning and volume control knobs on the front end of said slide, independently adjustable cams on said slide, a tuner adjusting rocker positioned for adjustment by one of said cams, a volume controlling rocker positioned for adjustment by another of said cams, adjusting connections from said tuning and volume control knobs to said tuning and volume control cams, a wave band selecting lever on said slide in back of said control knobs, a cam adjustably mounted on the slide and operably connected with said lever and a wave band selecting rocker positioned to be adjusted by said last mentioned cam.

11. In apparatus of the character disclosed for turning on and effecting volume control adjustments of a radio receiver, a tuner and volume control actuating slide, tuning and volume control knobs on the front end of said slide, independently adjustable cams on said slide, a tuner adjusting rocker positioned for adjustment by one of said cams, a volume controlling rocker positioned for adjustment by another of said cams, adjusting connections from said tuning and volume control knobs to said tuning and volume control cams, a control switch throwing means therefor and a fixed cam on said slide for actuating said switch throwing means at a predetermined point in the operation of the slide, regardless of the adjustments of said adjustable cams.

12. In apparatus of the character disclosed, an instrument adjusting slide, cams at the inner end of the same and above and below the same and instrument setting rockers positioned for operation by said end and by said upper and lower cams and thereby arranged to substantially balance the operation loads on said slide.

13. In combination, an instrument adjusting slide, concentrically arranged shaft elements mounted on said slide, finger holds on the outer ends of said concentric shaft elements for effecting independent rotary adjustments of the same, adjustable cams on said slide and operably connected with the respective shaft elements and instrument adjusting rockers positioned for engagement and operation by said cams.

14. In combination, an instrument adjusting slide, concentrically arranged shaft elements mounted on said slide, finger holds on the outer ends of said concentric shaft elements for effecting independent rotary adjustments of the same, adjustable cams on said slide and operably connected with the respective shaft elements, instrument adjusting rockers positioned for engagement and operation by said cams, a rack and pinion operating connection from the outermost of the concentric shaft elements to one of the adjustable cams and gear elements on the other shaft elements for effecting adjustments of the other cams.

15. An instrument adjusting slide having a branched inner end, separately adjustable cams on the branches of said slide, rockers positioned for actuation by said cams and independent adjusting connections extending from the front end of the slide to the respective cams.

16. An instrument adjusting slide having outer

and inner bearing lugs projecting from one side of the same, a central shaft projecting through said bearing lugs and having its inner end journalled in the inner bearing lug, a tubular shaft about said central shaft and having its outer end journalled in the outer bearing lug, an outer tubular shaft on said first mentioned tubular shaft at the inner side of said outer bearing lug, means connected with the outer end portions of said inner shaft, intermediate tubular shaft and outer tubular shaft for independently adjusting the same, gears on the inner end portions of said inner shaft and intermediate tubular shaft, adjustable instrument setting devices mounted on said slide and connected with the respective gears, an instrument setting element adjustably mounted on the slide adjacent the outer tubular shaft and gearing connections from said outer tubular shaft to said last mentioned adjustable instrument setting element.

17. An instrument adjusting slide, a selector lever pivotally mounted on said slide and having a projecting lug at one side, a wall through which said slide projects, said wall having notches therein spaced to receive and retain the lug of said lever in different selected positions when the slide is pushed inward, said lug being clear of said wall when the slide is in projected position, thus to permit free selecting adjustments of said lever when the slide is projected.

18. Mechanism for adjusting and setting, comprising a slide free for hand operation, rockers positioned on different centers and arranged for individual actuation by said slide and a solenoid for effecting operation of the slide independently of hand operation.

19. Apparatus of the character disclosed comprising a plurality of slides for effecting adjustments of different members, the inner ends of said slides being separated into substantially parallel branches, springs disposed about certain of said branches for projecting the slides, solenoids having cores connected with certain of the branches for retracting the slides, rockers journalled transversely on the slides in line with the branches and having passages through which the branches pass, cams adjustably mounted on the branches in position to engage and adjust the rockers, and means on the slides for retaining said cams in their positions of adjustment on the slides.

20. Apparatus of the character disclosed comprising a plurality of slides for effecting adjustments of different members, the inner ends of said slides being separated into substantially parallel branches, springs disposed about certain of said branches for projecting the slides, solenoids having cores connected with certain of the branches for retracting the slides, rockers journalled transversely of the slides in line with the branches and having passages through which the branches pass, cams adjustably mounted on the branches in position to engage and adjust the rockers, means on the slides for retaining said cams in their positions of adjustment on the slides, time control means for effecting energization of selected solenoids at predetermined selected times and said slides having exposed handles on the outer ends of the same and by which said slides may be depressed by hand at any time independently of said solenoids and time control means.

21. Apparatus of the character disclosed comprising a plurality of slides for effecting adjustments of different members, the inner ends of

11

said slides being separated into substantially parallel branches, springs disposed about certain of said branches for projecting the slides, solenoids having cores connected with certain of the branches for retracting the slides, rockers journaled transversely of the slides in line with the branches and having passages through which the branches pass, cams adjustably mounted on the branches in position to engage and adjust the rockers, and means on the slides for retaining said cams in their positions of adjustment on the slides, the branches of each slide being three in number and the cams being carried by the upper and lower branches and the springs being disposed on the intermediate branches.

22. Apparatus of the character disclosed comprising a plurality of slides for effecting adjustments of different members, a rocker in the line of movement of said slides and adapted for connection with a member to be adjusted, cams on said slides in position to engage and actuate said rocker, cam shoulders on said slides, a control switch, a solenoid having a core for shifting said control switch in one direction and a rocker for throwing said switch in the opposite direction and positioned to be engaged and actuated by the cam shoulder on any one of said slides and whereby said control switch will be thrown in the opposite direction from that in which it is thrown by said solenoid upon actuation of any one of said slides.

23. Apparatus of the character disclosed comprising a plurality of slides for effecting adjustment of different members, a rocker in the line of movement of said slides and adapted for connection with a member to be adjusted, cams adjustably mounted on said slides in position to engage and actuate said rocker, means on said slides for adjusting the cams thereon and interlocking means for holding said adjusting means inoperative when the slides are actuated to engage said cams with the rocker and to free said adjusting means for adjustment when the slides are in position with the cams thereon free of said rocker.

24. Apparatus of the character disclosed comprising a plurality of slides for effecting adjustments of different members, rockers in the line of movement of said slides and adapted for connection with the members to be adjusted, cams adjustably mounted on said slides in position to engage and actuate the respective rockers, concentric shafts on each of said slides and gearing actuated thereby for independently adjusting the cams thereon and means at the outer ends of said slides for independently turning the concentric shafts thereon.

25. Apparatus of the character disclosed comprising a plurality of movable station selecting members, a rocker in the line of movement of said members and adapted for connection with a member to be adjusted, cams on said slides in position to engage and actuate said rocker, cam shoulders on said members, a rocker positioned for actuation by any one of the cam shoulders on the different station selecting members, an "on" switch arranged to be operated in one direction by said last mentioned rocker, an "off" magnet for actuating said switch in the opposite direction and selectively operable devices for effecting energization of said "off" magnet upon

12

operation of a preselected station selecting member.

5 26. Apparatus of the character disclosed comprising a plurality of movable station selecting members, a rocker in the line of movement of said members and adapted for connection with a member to be adjusted, cams on said slides in position to engage and actuate said rocker, cam shoulders on said members, a rocker positioned for actuation by any one of the cam shoulders on the different station selecting members, an "on" switch arranged to be operated in one direction by said last mentioned rocker, an "off" magnet for actuating said switch in the opposite direction and selectively operable devices for effecting energization of said "off" magnet upon operation of a preselected station selecting member and including time control means and solenoids controlled thereby for actuating said station selecting members.

10 27. In apparatus of the character disclosed, a plurality of spring projected, arbitrarily manually operable station selecting slides, a plurality of independently adjustable cams on each of said slides, independently operable means for individually adjusting the cams thereon, rockers positioned for actuation by said independently adjusted cams, electromagnets for operating said slides, time control means for selectively energizing different electromagnets to effect timed operation of said slides, a control switch, means for actuating said switch in one direction and arranged for operation by any one of said slides and an electromagnet for actuating said control switch in the opposite direction and arranged for actuation by said time control means and whereby said control switch may be operated in one direction by any one of said slides and be operated in the opposite direction by said switch actuating electromagnet, all under control of said time control means.

FREEMAN H. OWENS.
